(57) **CLAIM**

The ornamental design for a headgear, as shown and described.

DESCRIPTION

FIG. 1 is a top view of the headgear showing my new design; FIG. 2 is a bottom view thereof; FIG. 3 is a right side view thereof; FIG. 4 is a left side view thereof; FIG. 5 is a rear side view thereof; FIG. 6 is a front view thereof; FIG. 7 is a front, perspective view thereof; FIG. 8 is a rear perspective view thereof with the headgear shown in the wearable position; and, FIG. 9 is a top perspective view thereof with the headgear shown in the wearable position.

The broken lines depicting the head in FIGS. 8 and 9 represent environmental subject matter and form no part of the claimed design, and the broken line depicting the cords shown in FIGS. 1-9 illustrate portions of the headgear that form no part of the claimed design. The chin strap is shown with a symbolic break in its length in FIGS. 1-4, 7, and 8. The appearance of any portion of the article between the break lines form no part of the claimed design.
